J. W. GUNN

AUTOMOBILE SIGNAL CASING

Filed April 19, 1927

Inventor
John W. Gunn,

By *James O'Brien*
Attorney

UNITED STATES PATENT OFFICE.

JOHN WALTER GUNN, OF JERSEY CITY, NEW JERSEY.

DESIGN FOR AN AUTOMOBILE SIGNAL CASING.

Application filed April 19, 1927. Serial No. 21,844. Term of patent 14 years.

To all whom it may concern:

Be it known that I, JOHN WALTER GUNN, a citizen of the United States, residing at Jersey City, in the county of Hudson and State of New Jersey, have invented a new, original, and ornamental Design for an Automobile Signal Casing, of which the following is a specification, reference being had to the accompanying drawing, forming part thereof.

Figure 1 is a front elevation of an automobile signal casing, showing my new design.

Figure 2 is a side elevation of an automobile signal casing, showing my new design.

I claim:

The ornamental design for an automobile signal casing as shown.

JOHN WALTER GUNN.
